(57) **CLAIM**

The ornamental design for an envelope for greeting cards and invitations, as shown and described.

DESCRIPTION

FIG. 1 is a top view of a first embodiment of an envelope for greeting cards and invitations shown unfolded;

FIG. 2 is a back view thereof;

FIG. 3 is a top view of the envelope for greeting cards and invitations of FIG. 1 when folded;

FIG. 4 is a back view, thereof;

FIG. 5 is an isometric view of FIG. 3;

FIG. 6 is a top view of a second embodiment of an envelope for greeting cards and invitations shown unfolded;

FIG. 7 is a back view thereof;

FIG. 8 is a top view of the envelope for greeting cards and invitations of FIG. 6 when folded;

FIG. 9 is a back view, thereof; and,

FIG. 10 is an isometric view of FIG. 8.

The evenly segmented broken lines on the perimeter of the article depict portions of the envelope for greeting cards and invitations that are not included in the claim. The horizontal dash dot dash broken lines in FIGS. 1, 2, 6 and 7 denote fold lines.

In FIGS. 1, 3, 5, 6, 8 and 10, the evenly segmented broken lines illustrate mailing features that form no part of the claimed design. The dash dash dot broken lines in FIGS. 2 and 7 illustrate the environment of adhesive strips that form no part of the claimed design. The curved segment lines in FIGS. 1, 3-6 and 8-10 are symbolic of a fabric in contrast to portions rendered in linear shading in FIGS. 2, 6, 7 and 9 which symbolizes paper material.
